[57] ABSTRACT

This disclosure relates to a novelty safety closure comprising a fitment and a cap for assembly together and telescopic press application onto a container finish, the cap having means reinforcing a part of the fitment against outward deflection, the fitment having an interior surface reducing in diameter from a leading surface portion thereof toward the opposite end thereof, the leading surface portion in the area of the reinforcing means having a diameter sufficient to permit telescopic assembly of the cap and fitment on an associated container finish with little initial resistance to the relative telescopic movement of the diminishing diameter of the fitment above said surface portion with thereafter increasing resistance to a point of interference which is offset by radial outward deflection of the fitment above said surface portion, and the fitment terminates at the opposite end thereof in means for axially opposing abutment of an associated container finish thereby precluding unauthorized removal of the fitment and/or cap from a container finish.

The finish also includes means for axially opposing abutment of the fitment abutment means, and in a preferred embodiment of the invention the finish and fitment abutment means are opposed annular shoulders.

FIG.1

FIG 2

FIG. 3

FIG.4

SAFETY CLOSURE FITMENT AND FINISH

This application is a continuation-in-part of commonly assigned application Ser. No. 260,105, filed June 6, 1972 in the name of Frank R. Lecinski, Jr., and now U.S. Pat. No. 3,836,034.

Safety closures have recently come into prominence because of the desirability of federal, state and local agencies to preclude or substantially reduce accidental illness and/or death resulting from the consumption of packaged products. A most notable example is that of infants or younger children opening aspirin bottles and consuming the contents thinking it to be candy.

It is because of such typical overdosages that many conventional so-called "childproof" closures or simply "safety" closures have been developed. Unfortunately, such conventional safety closures generally include a variety of disadvantages, the most common of which is the relatively high manufacturing cost involved due to intricate container and/or closure design. This is particularly true in the production of small lots wherein the cost of the dies themselves, in the case of injection and/or compression molding techniques, is prohibitive from a cost standpoint.

Another disadvantage is the difficulty in intentionally opening many typical safety closures, the most common of which is various varieties of "palm and twist" types. This has been found to be true when such closures are attempted to be opened by older or uneducated persons, particularly if they are handicapped or, for example, suffering from arthritis. It is for these and other reasons that the Food and Drug Administration lists among its requirements for safety closures not only criteria for precluding the accidental removal of a closure from an associated container, but criteria for the relatively easy removal of safety closures when such removal is intentionally desired. For example, under the Poison Prevention Packaging Act (PPPA) the Food and Drug Administration published as its protocol a minimum level of effectiveness at 85% for children receiving no opening instructions and 80% after instructions. Indications are that all products subject to the PPPA will have to conform to the same standard, coupled with a requirement that 90% of the adults tested must also be able to open and reclose childproof or child-resistant packages.

Another disadvantage of conventional safety closures is the ability thereof to close but not hermetically seal associated containers. This is not overly disadvantageous when solid products are packaged, such as aspirin, solid preparations harmful to health but not hygroscopic, etc. However, under the PPPA such liquid products as furniture polish, oil of wintergreen, sulfuric acid, harmful hygroscopic solid substances, etc., will necessarily have to be packaged in accordance with the provisions of this Act.

In view of the foregoing disadvantages of conventional safety or child resistant closures, it is a primary object of this invention to provide a safety closure which not only precludes inadvertent and/or accidental operation thereof, but permits ease of removal when intentionally desired, and can be used with liquid or solid products.

The latter object is achieved by providing a safety closure which comprises a fitment and a cap assembled together by relative telescopic press application, the cap having means reinforcing a part of the fitment

against outward deflection, the fitment having an interior surface reducing in diameter from a leading surface portion thereof toward the opposite end thereof and the leading surface portion in the area of the reinforcing means having a diameter sufficient to permit telescopic assembly of the cap and fitment on an associated container finish with little initial resistance to the relative telescopic movement and the diminishing diameter of the fitment above the surface portion thereafter increasing the resistance of telescopic assembly to a point of interference which is offset by radial outward deflection of the fitment above the surface portion thereby achieving rapid assembly of the components upon a container finish, and the fitment further including means at the opposite end thereof for axially opposing abutment of an associated container finish thereby precluding unauthorized removal of the fitment and/or cap from a container finish by persons when initiated in the operation of the closure.

Still another object of this invention is to provide a novel closure of the type set forth wherein the closure is secured to threads of the fitment by lugs of the peripheral skirt, and the lugs constitute at least in part said reinforcing means.

Another object of this invention is to provide novel safety closure of the type heretofore defined in combination with a novel container finish having means between the finish and inner peripheral fitment surface for spacing a major portion of the latter away from the finish thereby allowing a simple press-on of the cap and fitment assembly to the associated container and to provide reduced frictional purchase to permit rotation of the fitment and closure in unison.

In further keeping with this invention it is an object to provide a novel dimensional relationship between oppositely facing annular walls of the fitment and a finish bead, with the over-all effect thereof permitting the assembly of the fitment upon the container finish with the annular walls sandwiched between the finish bead and an associated finish shoulder.

With the above and other objects in view that will hereinafter appear, the nature of the invention will be more clearly understood by reference to the following detailed description, the appended claimed subject matter, and the several views illustrated in the accompanying drawings.

In the drawing:

FIG. 1 is a fragmentary side elevational view with portions broken away and shown in section for clarity, and illustrates a fitment and a container finish with the pre-assembled closure being removed from the fitment to gain access to a product within the container.

FIG. 2 is an enlarged sectional view of the fitment, closure and container of FIG. 1 taken along line 1-1 thereof, and illustrates a pair of annular abutment means in axially opposed spaced relationship in the form of a bead and shoulder of the container finish between which is sandwiched the fitment carrying the closure.

FIG. 3 is a fragmentary side elevational view again with portions broken away and shown in section for clarity, and illustrates a fitment, a container and a separable container finish with the pre-assembled closure being removed from the fitment to gain access to a product within the container.

FIG. 4 is an enlarged sectional view of the fitment, closure, container finish and container of FIG. 3 taken

along line 3-3 thereof, and illustrates the container finish having a bead interlocked with a groove of the fitment for maintaining the components in slip-fit assembled relationship.

A novel safety closure constructed in accordance with this invention is generally designated by the reference numeral 10, and includes a closure or cap 11 and a fitment 12 therefor. When united or pre-assembled in a manner to be described more fully hereinafter the safety closure 10 is assembled upon a container 13.

The closure 10 is of a conventional construction and includes an end panel 14, a depending peripheral skirt 15, and an inwardly upwardly and downwardly directed curl or bead 16 which is interrupted to define three locking lugs 17 of which only one is illustrated in the drawing. The locking lugs 17 are disposed equally about the periphery of the cap 11. The cap 11 is preferably constructed from metallic material and sealing compound 18 (FIG. 2) may be applied to the interior in a conventional manner if the contents of the container 13 are liquid. Otherwise the sealing compound 18 may be eliminated, if found necessary or desirable, or substituted for with paper liner material.

The fitment 12 is preferably constructed from resilient polymeric or copolymeric material, such as polyethylene, and includes a generally annular body 20 having axially opposite open ends 21, 22 between which are respective inner and outer peripheral surfaces 23, 24, respectively, the former being a generally frusto-conical lead surface which cooperates with the container 13 during assembly in a manner to be described hereinafter.

An annular axially upwardly facing terminal wall 25 of the fitment 12 functions to secure the fitment 12 to the container 13, as will be described more fully herein-after. The fitment 12 additionally includes three equally spaced threads 26 (FIG. 1) which each cooperates with one of the lugs 17 for securing the closure 11 upon the fitment 12 upon the preassembly thereof prior to being capped upon the container 13. Each lug 17 rides beneath its associated thread 26 and is drawn or cammed downwardly by an inclined lead wall 27 which levels out at 28 and terminates at an outwardly directed rib or stop 30.

The body 20 of the fitment 12 terminates adjacent the end 22 in an axially downwardly facing terminal wall 31 and a depending peripheral skirt 32 whose outer peripheral surface includes vertical ribs 33 and whose bottom includes a plurality of projections 34 which function to facilitate the assembly of the closure 11 upon the fitment 12, as will be described more fully herein-after. An opening 35 is formed beneath each thread 26 in a conventional manner during the injection molding of the fitment 12.

The container or bottle 13 includes a lower bead 36 which merges with a frusto-conical wall 37 (FIG. 2) of a container neck or finish 38. Above the frusto-conical wall 36 is another annular bead 39 having an axially downwardly facing wall 40 opposing the wall 25 of the fitment 12. The finish 36 terminates in an upper annular face or surface 41 which is slightly above the wall 25 of the fitment 12 when the elements are in assembled relationship, as indicated best in FIG. 2, it being noted that only the finish 38 and adjacent elements 39, 41 is embedded in the sealing compound 18 of the cap 11.

Though briefly described hereinafter, the closure 11 and fitment 12 are assembled by first moving the same axially relative to each other such that each lug 17 becomes positioned adjacent its associated thread 26 with the curl 16 resting atop the uppermost surface (unnumbered) of the radial wall (also unnumbered) between the peripheral skirt 32 and the body wall 20 of the fitment 12. Thereafter, the closure 11 and the fitment 12 are rotated relative to each other at which time the lugs 17 ride along the inclined lead walls 27 and the succeeding walls 28 until each lug 17 contacts a stop 30.

When assembled automatically the ribs 33 and teeth or projections 34 serve as gripping surfaces for a chuck or similar holder to prevent the fitment 12 from rotating upon the rotation of the closure 11.

Once the container 13 has been filled with a desired product, be it solid or liquid, the packager simply telescopes the pre-assembled closure 11 and fitment 12 downwardly upon the finish until the fitment 12 seats

20 in sandwiched relationship between the frusto-conical wall 37 and the annular wall 40 of the container finish 38, in the manner best illustrated in FIG. 2. However, in order to do this a definite relationship has been established between what has been heretofore termed the

25 frusto-conical lead surface 23 of the fitment 12, the external diameter of the finish bead 39, and the relative position of the lugs 17 relative to the bead 39 during the assembly operation. Referring specifically to FIG. 2 a line L1 designates a development of the maximum diameter of the finish bead 39. The line L2 which is normal to the line L1 is shown intersecting the latter at a point P1 at which the inner diameter of the surface 23 corresponds to the maximum diameter of the bead 39. It will be noted that the line L2 is also above each

30 lug 17. Thus, as the fitment is initially positioned with its pre-assembled closure 11 upon the finish 38 of the container 13 there is little or no resistance since the diameter of the leading surface 23 below the line L2 is larger than the diameter of the bead 39 thus movement 40 of the pre-assembled closure 11 and fitment 12 to the final position shown in FIG. 2 is virtually accomplished in the absence of initial resistance by the fitment 12 of the closure 11. Moreover, at this point the bead 39 is adjacent the most rigid area of the pre-assembled unit

45 since the area immediately below the line L2 is reinforced against outward deflection by the thicker material of the fitment 12 in the area of the threads 26, and the reinforcement offered against deflection of the fitment 12 by the lug 17 and the associated curl 16 of the cap 12. This area is, however, virtually passed with little resistance as the bead 39 approaches point P1 and passes the same. During this passage resistance is lessened since lesser reinforcement of the fitment 12 occurs above the line L2 than below the same. Accordingly,

50 the upper portion of the body 20 above the line L2 will deflect radially outwardly as the finish bead 39 is guided toward and beyond terminal wall 25 by the leading surface 23. Once the bead 39 reaches the terminal wall 25 it rebounds thereover, in the manner best illustrated in FIG. 2. Thus, the relationship of the components permit as in no other known assembly of this type the unified assembly of the pre-assembly 11, 12 upon the container finish 38.

55 As was heretofore noted, the closure of this invention is designed specifically to achieve a seal when the package contents are liquids or hygroscopic solid substances harmful to human beings. An effective seal is achieved

upon assembling the filled container 13, the closure 11 and fitment 12 primarily because only the container finish is embedded in the sealing compound 18, as opposed to the seal achieved with respect to FIG. 4, as will be described further hereinafter. Thus, under most any adverse conditions of packaging, storing, shipment, etc., seepage and/or slippage is precluded until such time as intentional opening of the closure 10 takes place.

The diameter of the bead 39 will temporarily cause the fitment 12 and particularly the body 20 thereof to flex radially outwardly above the line L2 during assembly as was heretofore described but upon the bead 39 reaching the seating thereof above the wall 25 the fitment 12 will assume its nonstressed condition at which design tolerances permit the fitment 12 to rotate relatively free with respect to the container 13. When thus closed a gap G is formed between the exterior surface of the finish 38 of the container 13 and the inner lead surface 23 of the fitment 12 due to the manner in which the inmost edge (unnumbered) of the wall 31 bears on the frustoconical wall 37 (FIG. 2). The wall 37 prevents the body 20 from moving inwardly and thus reduces frictional purchase between the fitment and the finish to create a looseness for additionally permitting unitized rotation of the cap 11 and fitment 12. The wall 37 also continually urges the fitment 12 upwardly and maintains abutment between the walls 40 and 25.

Should the filled and capped container 13 come into the hands of a youngster, the most natural inclination is to either pull the safety closure 10 axially, rotate the closure 11 and/or the fitment 12, or both. A straight pull exerted on the cap 11 and/or the fitment 12 precludes pulling off the assembly because of the interlock between the wall 25 of the fitment 12 and the wall 40 of the bead 39. Rotation in a clockwise direction as viewed in FIG. 1 causes simultaneous or unified rotation of the entire safety cap 10 since each lug 17 is engaged with the wall 30 and thus rotation imparted to the closure 11 is transferred to the fitment 12 and vice versa. Similarly, rotation in the opposite direction (counterclockwise as viewed in FIG. 1) results in the lugs 17 maintaining frictional bearing purchase against the walls 28 and again unified rotation of the closure 11 and fitment 12 is effected. Thus a youngster or one uninitiated would find it virtually impossible to remove the safety closure 10 from the container 13. However, in order to accomplish the latter the exposed peripheral skirt 32 of the fitment 12 is grasped in one hand whereas the closure 11 is rotated counter-clockwise clear of the threads 26. The closure 11 is thereafter merely lifted vertically upwardly for complete removal to gain access to the contents packaged within container 13. In the open condition of the container 13 and fitment 12 the sealing compound 18 is removed with the closure 11. In this same open condition the end wall 41 and the bead 39 of the container 13 is positioned above the end face 25 of the fitment 12 to assure that the fitment does not interfere with the sealing, in the manner illustrated in FIG. 2, as would might otherwise happen if the end face 25 thereof projected beyond the end wall 40 of the container 13.

Another container, fitment and closure is illustrated in FIG. 4 and like primed reference numerals have been applied thereto to indicate elements identical to those of the combination 10 of FIGS. 1 and 2. The differences between the structure of FIGS. 3 and 4 and

that of the structure of FIGS. 1 and 2 is (a) the inclusion on the inner surface 23' of the fitment 12' of a groove 45 which receives the bead 39' of the finish 38'; (b) the provision of an integral end panel 46 in the finish 38' which is provided with an axial dispensing aperture 47 and (c) the formation of the container finish 38' as an element separate and apart from a container body 47 which is constructed from metallic material and has double seamed at 48 thereto an annular closure 49 terminating in a flange 50 to which is snap-secured a lower end portion 51 of the container finish 38'. The structure at elements 46 through 51 is self-evident and details of the groove 45, the bead 39' and the sealing compound 18' associated with the closure 11' will be found more specifically detailed in commonly assigned application Ser. No. 260,105, filed June 6, 1972 in the name of Frank H. Lecinski, Jr. and now U.S. Pat. No. 3,836,034.

While preferred forms and arrangements of parts have been shown in illustrating the invention it is to be clearly understood that various changes in details and arrangement of parts may be made without departing from the spirit and scope of this disclosure.

I claim:

1. A closure comprising a tubular fitment and a cap assembled together for subsequent telescopic press application onto a container finish, said fitment having a frusto-conical interior surface said cap having an end panel and a peripheral skirt with means reinforcing a part of said fitment against outward deflection, said tubular fitment having an interior surface reducing in diameter from a leading surface portion thereof remote from said end panel toward the opposite end thereof of adjacent said end panel, said leading surface portion in the area of said reinforcing means having a diameter sufficient to permit telescopic assembly of the cap and fitment on an associated container finish with little initial resistance to the relative telescopic movement, and the diminishing diameter of said fitment above said surface portion thereafter increasing the resistance of telescopic assembly to a point of interference which if offset by radial outward deflection of said fitment above said surface portion, and said fitment terminates at said opposite end thereof in means for axially opposing abutment of an associated container finish thereby precluding unauthorized removal of said fitment and/or cap from a container finish.

2. The closure as defined in claim 1 wherein said reinforcing means additionally defines means for releasably securing said cap to said fitment.

3. The closure as defined in claim 1 wherein said reinforcing means additionally defines lug means for releasably securing said cap to said fitment.

4. The closure as defined in claim 1 including a container having a finish, and said finish also includes means for axially opposing abutment of said fitment abutment means.

5. The closure as defined in claim 1 wherein said fitment abutment means is a terminal annular face of said fitment opposite end.

6. The closure as defined in claim 4 wherein said fitment abutment means is a terminal annular face of said fitment opposite end.

7. The closure as defined in claim 4 wherein said finish abutment means is a circumferential bead.

8. The closure as defined in claim 5 wherein said finish abutment means is a circumferential bead.

9. The closure as defined in claim 8 wherein said circumferential bead has an exterior diameter greater than the interior diameter of said fitment interior surface at said fitment terminal annular face.

10. A closure comprising a tubular fitment and a cap assembled together for subsequent telescopic press application onto a container finish, said fitment having a frusto-conical interior surface said cap having an end panel and a peripheral skirt with means reinforcing a part of said fitment against outward deflection, said tubular fitment having an interior surface reducing in diameter from a leading surface portion thereof remote from said end panel toward the opposite end thereof adjacent said end panel, said leading surface portion in the area of said reinforcing means having a diameter sufficient to permit telescopic assembly of the cap and fitment on an associated container finish with little initial resistance to the relative telescopic movement, and the diminishing diameter of said fitment above said surface portion thereafter increasing the resistance of telescopic assembly to a point of interference which is offset by radial outward deflection of said fitment above said surface portion, said fitment terminates at said opposite end thereof in means for axially opposing abutment of an associated container finish thereby precluding unauthorized removal of said fitment and/or cap from a container finish, and means for snap-securing a metallic container body to said container finish.

11. The closure as defined in claim 10 including a panel spanning the container finish and having a dispensing aperture therein.

12. The closure as defined in claim 1 in combination with a container body having a finish, said finish includes an exterior surface surrounded by said interior frusto-conical fitment surface, and a circumferential gap between said last-mentioned two surfaces extend-

ing axially substantially entirely the axial length of said interior frusto-conical fitment surface.

13. The closure as defined in claim 12 wherein said finish also includes means for axially opposing abutment of said fitment abutment means, and said finish abutment means are axially opposing spaced annular walls between which are sandwiched said fitment with each of axially opposite end faces of said fitment abutting a respective adjacent one of said annular walls.

14. A closure comprising a tubular fitment and a cap assembled together for subsequent telescopic press application onto a container finish, said fitment having a frusto-conical interior surface, said cap having an end panel and a peripheral skirt with means reinforcing a part of said fitment against outward deflection, said tubular fitment having an interior surface reducing in diameter from a leading surface portion thereof remote from said end panel toward the opposite end thereof adjacent said end panel, said leading surface portion in the area of said reinforcing means having a diameter sufficient to permit telescopic assembly of the cap in fitment on an associated container finish with little initial resistance to relative telescopic movement, and the diminishing diameter of said fitment above said surface portion thereafter increasing the resistance of telescopic assembly to a point of interference which is offset by radial outward deflection of said fitment above said surface portion.

15. The closure as defined in claim 14 in combination with a container body having a finish, said finish includes an exterior surface surrounded by said interior frusto-conical fitment surface, and a circumferential gap between said last-mentioned two surfaces extending axially substantially entirely the axial length of said interior frusto-conical fitment surface.
